UNITED STATES PATENT OFFICE.

JOSEPH W. CLEMENT, OF LOWELL, MASSACHUSETTS.

BANJO.

SPECIFICATION forming part of Letters Patent No. 470,986, dated March 15, 1892.

Application filed March 7, 1891. Serial No. 384,076. (No model.)

To all whom it may concern:

Be it known that I, JOSEPH W. CLEMENT, a citizen of the United States, residing at Lowell, in the county of Middlesex and Commonwealth of Massachusetts, have invented a certain new and useful Improvement in Banjos, Banjorines, and Similar Instruments, of which the following is a specification.

My invention relates to banjos, banjorines, and similar instruments; and it consists in the devices and combinations hereinafter described and claimed, the objects of which are to conceal the devices which regulate the tension of the head, to move the tail-piece with the tension-hoop, to improve the tone of the instrument, and to secure the banjo from slipping in the lap of the operator.

In the accompanying drawings, Figure 1 is an isometric perspective view of a banjo provided with my improvement, the free or outer end of the neck or arm being omitted; Fig. 2, a section on the line 2 2 in Fig. 3 through the rims, tail-piece, sounding-bar, head, and hoops, and a side elevation of one of the tension-hooks, the holding-screw, and the tail-pin; Fig. 2^a, an outside elevation of a part of the outer rim, part of the tension-hoop, the tail-pin and its nut, and a transverse section of the tail-piece, showing, also, in dotted lines the upper parts of two tension-hoops and the groove in the tension-hoop; Fig. 2^b, an isometric perspective view of the tail-pin and its nut; Fig. 3, a reversed plan of the banjo, omitting the neck, except the part adjacent to the outer rim, and showing the nuts which secure the sounding-bar to the neck; Fig. 3^a, an isometric perspective view of the rest detached. Figs. 4 and 5 represent modifications, Fig. 4 being an outside elevation of a part of the rims, tension-hoop, and some tension-hooks, and Fig. 5 being a section on the line 5 5 in Fig. 4 of the rims, head, and tension-regulating devices.

The neck or arm A, strings B, bridge C, and tail-piece D are of the usual construction and operation.

The banjo represented is provided with two annular rims and an outer rim E, of metal, having an internal annular flange e integral therewith and arranged at a distance from the lower edge of said rim E greater than the

thickness of the tension-nuts j², hereinafter mentioned, the inner edge of said flange e being turned up at e' substantially parallel with the body of the rim E. An inner wooden rim F is arranged concentrically with the rim E and rests upon the flange e, and is rabbeted at f' to receive the upturned inner edge e' flush with the inner surface of said wooden rim. The outer upper edge of the rim F is 60 provided with a groove f, arc-shaped in cross-section to receive a bearing-hoop f², preferably of wire, over which the skin or head G is stretched. Another hoop or ring H, preferably of wire and sometimes called a "flesh-hoop," is wrapped in the edge of the head G, and said head is strained by pressing a tension-hoop I, preferably metallic, down upon said hoop H by means of "bracket-hooks" or tension-hooks J, arranged at the usual intervals and provided at their upper ends with hooks j, which enter an annular groove i in the external face of the tension-hoop I. The shanks of the hooks J are arranged in an air-space E' between the rims E and F and extend downward through the flange e, and at their lower ends are screw-threaded at j' to receive nuts j², which turn on said screw-threaded portions against the under side of said flange e and draw the tension-hoop I and 70 ring H toward the flange. The tension-hoop I is wedge-shaped in cross-section or very slightly downwardly tapering externally, so that when drawn between the rims E F it completely fills the upper part of the space 75 between said rims and prevents any rattling of the parts.

The wooden and metallic rims combine the advantages of both materials and, with the space E' between them, form a sounding-chamber, which intensifies the sound of the instrument.

The sounding-bar L is a metallic rod instead of the wooden bar commonly used, and is provided at its upper end with an external screw-thread l, which engages a metallic nut l', inserted in a recess a in the back of the neck A, and the lower end of said sounding-bar is held in place by a screw l'', which passes through the above-named flange e of the outer rim E and into or through said sounding-bar. Another nut l³ is turned on said sounding-bar

near its upper end against the inner face of the rim E, and with said nut l' holds said rim and the lower end of the neck firmly in contact. This construction in effect makes the 5 rim and neck integral with each other and causes the vibrations of the neck to be more perfectly transmitted to the rims and head.

The external surface of the outer rim E is accessible in all its parts for cleaning purposes 10 and affords no lodgment for dirt, but is so smooth as to be in danger of slipping in the lap of the performer. I therefore provide a rest K, (shown in Figs. 3 and 3^a), the same consisting of an arc-shaped piece or crescent 15 k, adapted to rest upon the thigh of the operator and having its concave surface, if desired, lined with velvet k' or other cloth or material adapted to adhere to the clothing, and having a leaf-spring k² attached to the convex side of 20 said crescent k, as by rivets k³, about midway between the end of said crescent and spring, said spring, when the rest is detached from the rim E, normally curving into contact, or 25 nearly so, with the convex surface of said crescent. The outer ends of the spring k at the lower edge thereof are provided with upwardly-bent hooks k⁴, which may be placed over the lower edge of the rim E, as shown in Fig. 3, and held thereon by the tendency of 30 said spring to resume the shape of opposite curvature to which its elasticity tends to restore it, as shown in Fig. 3^a.

The tail-pin commonly used, provided at 35 its upper end with a hook or bend and running in a bracket projecting from the outer rim, may be used and may be adjusted in the ordinary manner by a nut turning on the lower end of said tail-pin against the lower side of said bracket; but I prefer to use the 40 T-shaped tail-pin M, (shown in Figs. 1, 2, 2^a, and 2^b), the lower part of which is provided with inwardly-curved branches m m', which hook under the flesh-hoop H and are retained in place by shanks of the two adjacent tension-hooks J, which pass up outside of said branches. The upper part of the tail-pin M passes through the usual hole in the tail-piece D and is screw-threaded at m² to enter a nut m³, which, being turned down, said tail-piece 45 50 clamps the latter against the top of the tension-rim, so that when once clamped the tail-piece moves with said tension-rim and needs no further adjustment, whereas the ordinary tail-piece requires to be adjusted in its supporting-bracket according to the height of the top of said tension-hoop above the top of the outer rim, and has therefore to be adjusted at each change of tension of the head.

The modified form (shown in Figs. 4 and 5) 60 differs from the form shown in Figs. 1 to 3 only in that the upper edge e² of the outer rim E², corresponding to the rim E in said Figs. 1 to 3, is turned inward under an external annular shoulder f³, with which the 65 wooden rim F' (otherwise like the rim F in Fig. 2) is provided, said inwardly-curved portion e² being provided with perforations e³

to allow the shanks of the tension-hooks J to pass through them, so that while retaining the sounding-chamber and the general construction first above described the outer surface of the rim is rendered less uniform and perhaps less monotonous in appearance.

I claim as my invention—

1. The combination of two rims arranged 75 one within the other, with an air-space between them, one of said rims having an annular flange and the other of said rims resting upon said flange, a skin or head resting upon the inner of said rims, a hoop wrapped in the outer edge of said head, a tension-hoop provided with an annular groove, tension-hooks entering said groove and provided with shanks having screw-threads and passing through holes with which said flange is provided, and 85 nuts turning on said shanks against said flange to draw said tension-hoop toward said flange and to stretch said head, as and for the purpose specified.

2. The combination of two rims arranged 90 one within the other with an air-space between them, one of said rims having an annular flange and the other of said rims resting upon said flange, a skin or head resting upon the inner of said rims, a hoop wrapped 95 in the outer edge of said skin and arranged in said air-space, a tension-hoop provided with an annular groove and arranged in said air-space, tension-hooks entering said groove and provided with shanks having screw-threads and arranged in said air-space and passing through holes with which said flange is provided, and nuts turning on said shanks against said flange to draw said tension-hoop into said air-space and to stretch said head, 100 105 as and for the purpose specified.

3. In a banjo or similar instrument, the combination of a rim, a neck having a recess, a nut arranged therein, a sounding-bar, having a screw-threaded end portion and passing 110 through holes with which said rim and neck are provided and engaging said nut, and another nut turning on said bar against the inner face of said rim, the other end of said bar being secured to the opposite side of said 115 rim, as and for the purpose specified.

4. A rest adapted to be attached to the rim of a banjo and having a surface adapted to adhere to the clothing of a performer on said banjo, as and for the purpose specified.

5. A rest provided with spring-hooks adapted to engage the rim of a banjo and to be held in engagement therewith by their elasticity, as and for the purpose specified.

6. A rest the body of which has a concave 125 surface to rest upon the thigh, said rest having a leaf-spring secured between its ends to said body and provided near its ends with hooks adapted to reach over the lower edge of the rim of a banjo and to be held in engagement therewith by the elasticity of said spring, as and for the purpose specified.

7. The tail-pin having a lower end adapted to engage the tension-hoop of a banjo or simi-

lar instrument and to be moved therewith and having an upper end adapted to engage the tail-piece of said banjo and to hold said tail-piece against the upper edge of said tension-hoop, as and for the purpose specified.

8. The combination of the tension-hoop, tension-hooks engaging said tension-hoop, the tail piece, and a tail-pin adapted to engage said tail-piece and having branches adapted to reach under said tension-hoop and to be held in place by the adjacent tension-hooks, as and for the purpose specified.

9. The combination of the tension-hoop, tension-hooks engaging said tension-hoop, the tail-piece, a tail-pin adapted to reach through

a hole with which said tail-piece is provided and having branches adapted to reach under said tension-hook and to be held in place by the adjacent tension-hooks, and a nut turning on said tail-pin above said tail-piece to hold said tail-piece in contact with said tension-hoop, as and for the purpose specified.

In witness whereof I have signed this specification, in the presence of two attesting witnesses, this 28th day of January, A. D. 1891.

JOSEPH W. CLEMENT.
